(57) **CLAIM**

The ornamental design for a handle, as shown and described.

DESCRIPTION

FIG. 1 is a perspective view of a handle showing new design; FIG. 2 is a right side view thereof, the left side view being identical;

FIG. 3 is a front view thereof, the rear view being identical; FIG. 4 is a perspective view of a mesh basket having the handle of my design installed on front and rear openings of the mesh basket;

FIG. 5 is a cross-sectional view taken along line 5-5 of FIG. 3; and,

FIG. 6 is a cross-sectional view taken along line 6-6 of FIG. 3. The broken lines illustrate environmental structure and form no part of the claimed design.

The drawings include surface shading that represents contour and not surface ornamentation.
